UNITED STATES PATENT OFFICE.

JAMES ALEXANDER GRAHAM AND JAMES ARTHUR McGEE, OF LORAIN, OHIO.

CAR-COUPING.

SPECIFICATION forming part of Letters Patent No. 588,821, dated August 24, 1897.

Application filed April 29, 1897. Serial No. 634,335. (No model.)

To all whom it may concern.

Be it known that we, JAMES ALEXANDER GRAHAM and JAMES ARTHUR McGEE, citizens of the United States, residing at Lorain, in the county of Lorain and State of Ohio, have invented certain new and useful Improvements in Car-Couplers; and we do declare the following to be a full, clear, and exact description of the invention, such as will enable others skilled in the art to which it appertains to make and use the same.

Our invention relates to car-couplers, and more particularly to means for connecting a chafing or buffer plate and a draw-head with the rear end of a locomotive-tender, and its novelty and advantages will be fully understood from the following description and claims when taken in conjunction with the annexed drawings, in which—

Figure 1 is a vertical longitudinal section of our improvements in position upon a locomotive-tender. Fig. 2 is a transverse section taken in the plane indicated by the line xx of Fig. 1. Fig. 3 is a top plan view. Fig. 4 is a detail perspective view of the draw-casting, and Fig. 5 is a detail perspective view of the chafing or buffer plate.

In the said drawings similar letters designate corresponding parts in all of the several views, referring to which—

A indicates a portion of a locomotive-tender, and B indicates the draw-casting, which forms part of our improvements and is connected to the rear end of the tender by bolts or other suitable means. This draw-casting B has the central socket a , with coincident apertures b in its upper and lower walls, the lugs c forming continuations of the side walls of the socket a , and having coincident apertures d and the vertical seats e at opposite sides of the socket a , which seats are of dovetail form in cross-section, with their lower and upper ends preferably open, and are slightly tapered or slightly reduced in width toward their lower ends, so as to support the arms of the chafing or buffer plate presently described.

C indicates the draw-head, which may be of any desired type, although the automatic knuckle type is preferred. This draw-head has a stem g , provided with vertical apertures h , said stem being arranged in the socket a

of the draw-casting and being secured therein by the pin D , which extends through the registered apertures $b\ h$ of the draw-casting and stem g , as shown. The said draw-head is also provided with the usual pin i , which is connected by a chain j with the arm k of a rock-shaft l , which is journaled in suitable bearings on the tender A and extends to opposite sides of the same in the usual manner.

E indicates the chafing or buffer plate, which is disposed transversely and rests in a plane above the draw-head C . This plate E has outer arms F , which are provided with end portions m , of dovetail form in cross-section, to take into the seats e of the draw-casting, and said plate also has the inner arms G , which are designed to rest between the lugs c of the draw-casting and be connected thereto by a bolt H , which takes through the apertures d of the said lugs and through apertures n in arms G , and is preferably secured against casual displacement by a nut p and a cotter-pin r , as shown, although other means may be employed for the purpose, if desired.

It will be observed from the foregoing that the chafing or buffer plate is connected with the draw-casting in such a manner that casual disconnection of the same is effectually prevented. While this is so the connection is such that it can be quickly and easily effected, and is further desirable because it permits of the chafing or buffer plate being readily disconnected from the draw-casting.

It will also be observed from the foregoing that the bolt H , which connects the arms G of plate E with the draw-casting, rests above and adjacent to the upper end of the pin D and effectually prevents casual rising of said pin, thus rendering it unnecessary to secure said pin with a split key or cotter-pin, as is usually done.

As better shown in Fig. 5, either one or both of the arms F on plate E are provided with large apertures s to permit of the bolt H being introduced to its operative position.

Having thus described our invention, what we claim is—

1. The combination of a draw-casting having vertical seats of dovetail form in cross-section in its face or outer side and also having lugs provided with transverse apertures, a chafing or buffer plate having arms pro-

vided with end portions of dovetail form in cross-section placed in the seats of the draw-casting and also having other arms provided with transverse apertures, and a bolt extending through the apertures of these latter arms and the apertures in the lugs of the draw-casting, substantially as specified.

2. The combination of a draw-casting having a socket provided with pin-holes in its lower and upper walls and also having lugs above and at the opposite sides of the socket provided with transverse apertures, a draw-head having a stem arranged in the socket and having a vertical aperture, a pin extending through the apertures in the socket-walls and stem, a chafing or buffer plate having arms provided with apertures, and a transverse bolt extending through the lugs of the draw-casting and the arms of the chafing or buffer plate and resting immediately above the pin so as to prevent the same from rising, substantially as specified.

3. The combination of a draw-casting having vertical seats of dovetail form in cross-section in its face or outer side and also having the socket between said seats and the apertured lugs above said socket, a draw-head having a stem arranged in the socket, a connecting-pin extending through the walls of the socket and the draw-head stem, a chafing or buffer plate having outer arms provided with end portions of dovetail form in cross-section placed in the seats of the draw-

casting and also having inner arms provided with transverse apertures, and a bolt extending through these latter arms and the apertures in the lugs of the draw-casting and resting above and in the same vertical plane as the connecting-pin to prevent the same from rising, substantially as specified.

4. The combination of a draw-casting having a socket, a draw-head having a stem arranged in the socket of the draw-casting, a connecting-pin taking through the walls of the socket and the stem of the draw-head, a chafing or buffer plate, and a bolt connecting said chafing or buffer plate and the draw-casting; said bolt being arranged above and in the same vertical plane as the connecting-pin to prevent rising of the same, substantially as specified.

5. The combination of a draw-casting having vertical seats of dovetail form in cross-section in its face or outer side, and a chafing or buffer plate having arms provided with dovetail end portions arranged in the seats of the draw-casting and other arms connected by a bolt with said draw-casting, substantially as specified.

In testimony whereof we affix our signatures in presence of two witnesses.

JAMES ALEXANDER GRAHAM.
JAMES ARTHUR McGEE.
